UNITED STATES PATENT OFFICE.

LAWRENCE W. FALCK, OF NEW YORK, N. Y.

GAFF-TOPSAIL FOR VESSELS.

SPECIFICATION forming part of Letters Patent No. 403,257, dated May 14, 1889.

Application filed January 30, 1889. Serial No. 298,046. (No model.)

To all whom it may concern:

Be it known that I, LAWRENCE W. FALCK, of the city, county, and State of New York, a citizen of the United States, have invented 5 certain new and useful Improvements in Gaff-Topsails for Vessels, of which the following is a specification.

The object of this invention is to facilitate the hauling in and furling of the gaff-topsails of vessels by so arranging the sail-controlling lines that one-half of the gaff-topsail is operated upon and then the other; and the invention consists of a gaff-topsail provided with a lower clew-line extending 15 along the lower and inner edges. An upper clew-line is attached to the upper edge of the gaff-topsail, a sheet-line and tack-line at the lower corners, and upper and lower halyards attached to the upper corner and to the inner 20 corner near the lowest mast-hoop, respectively, as will be fully set forth hereinafter, and finally pointed out in the claims.

In the accompanying drawings, Figure 1 represents a side elevation of my improved 25 gaff-topsail shown in position as hauled in and ready for furling, and Fig. 2 is a side elevation of the same shown as set.

Similar letters of reference indicate corresponding parts.

Referring to the drawings, A represents the fore, main, or mizzen mast of a vessel; B, the top-mast attached to the same; and C, a gaff, which is applied by its forked lower end to the mast A. A brace, D, is attached 30 to the upper end of the mast and to the gaff, and serves to support the latter in inclined position toward the mast A. The gaff-topsail E is set between the gaff, mast, and top-mast by the upper clew-line, f, lower clew-line, f', upper and lower halyards, g g', sheet-line f'', and tack-line f''. The upper clew-line, f, passes through eyes at the outer edge of the gaff-topsail E, and is connected by the sheet-line f'' to suitable belaying-pins. The 35 lower clew-line, f', passes through eyes at the lower and inner edges of the gaff-topsail E, up to near the lower mast-hoop, and then down to suitable belaying-pins.

The upper and lower halyards, g g', are at-

tached, respectively, to eyes of the upper 50 corner of the gaff-topsail, and to an eye near the lower mast-hoop of the gaff-sail at a point intermediately between the upper and lower corners of the same. The lower corner of the gaff-topsail is connected by a tack-line, f'', to belaying-pins. The lower halyard, g', passes through a sheave or pulley, g'', located in a slot of the top-mast B to its belaying-pins.

In setting the gaff-topsail, the sheet-line, 60 tack-line, upper and lower halyards, and the clew-lines are stretched tight as far as permitted by the sail and applied to their respective belaying-pins. For hauling in and furling the sail the lines are released, so that 65 the sail can be hauled in, as shown in Fig. 1, which takes place above the brace D, so as to facilitate the setting of the sail at either side of the same, according to the direction of the wind.

The new features of my improved sail are the arrangement of the lower clew-line and lower halyard, as by the same the sail can be more readily taken in and furled, as one-half of the sail at a time is handled—first, 75 the lower half, then the sheet loosened, and finally the upper half—while in setting the gaff-topsail the sheet-line is first hauled, then the upper half shortened, and, lastly, the lower half set by hauling down the tack-line. 80

Having thus described my invention, I claim as new and desire to secure by Letters Patent—

1. The combination, with a top-mast and gaff, of a gaff-topsail, an upper clew-line extending along the outer edge of the sail, a 85 lower clew-line extending along the lower and inner edges of the same, an upper halyard applied to the upper corner of the sail, a lower halyard attached to the gaff-sail near the lower mast-hoop, a sheet-line applied to 90 the outer corner, and a tack-line applied to the inner corner of the sail, substantially as set forth.

2. The combination, with a top-mast and gaff, of a gaff-topsail, an upper clew-line extending along the outer edge of the sail, an upper halyard attached to the upper corner 95 of the sail, a sheet-line attached to the outer

corner, a tack-line attached to the inner lower corner, a lower clew-line extending along the lower and inner edges of the sail up to the lowest mast-hoop, and a lower hal-
5 yard attached to the sail near the lower mast-
hoop and passing over a sheave or pulley of
the top-mast, substantially as set forth.

In testimony that I claim the foregoing as my invention I have signed my name in presence of two subscribing witnesses.

LAWRENCE W. FALCK.
